THUMB PIANO

James B. Wilson, Chicago, Ill., assignor to
Voice of The Flower, Ltd., Chicago, Ill.

Filed Feb. 6, 1970, Ser. No. 21,307

Term of patent 14 years

Int. Cl. D17—03

U.S. Cl. D56—1

FIG. 1 is a top plan view of the thumb piano showing my design;

FIG. 2 is a side elevational view the opposite side being substantially a mirror image thereof;

FIG. 3 is a bottom plan view thereof; and

FIG. 4 is a rear elevational view thereof.

I claim:

The ornamental design for a thumb piano, substantially as shown and described.
